BUILDING CORNER PIECE

Henry A. Mulderink, South Bend, Ind., assignor
to Mastic Asphalt Corporation, South Bend,
Ind., a corporation of Indiana

Application January 31, 1940; Serial No. 316,479

3 Claims. (Cl. 20—5)

This invention relates to a building corner piece, and more particularly to a building corner piece of simulated masonry siding of the type comprising a rigid insulation board base having a coating with combined waterproofing and decorative characteristics.

In the use of building covering material of this character, it is customary that the corners of a building be provided with a corner piece which overlies the ends of the wall panels adjacent to the building corner for a sufficient extent to provide a tight weather sealed joint at the building corner. Thus, if it is necessary to cut a panel adjacent the building corner and thereby expose the raw insulation board base thereof, which base is usually formed of material such as Celotex or Insulite, and is subject to liquid absorption and quick deterioration when exposed to the weather, the corner piece will protect such raw edges and consequently make the siding material weather tight throughout. However, it will readily be seen that there is one marked disadvantage in this practice; namely, the fact that the corner piece is off-set from the wall panels whose outer ends it overlaps.

Inasmuch as it is the primary object of the building covering material to simulate a natural masonry product, such as brickwork, which is not customarily laid up with off-sets at building corners, the use of the corner pieces is a definite disadvantage to the building covering material from the appearance standpoint.

While I propose to continue the use of the offset and overlapping corner piece, it is the primary object of my invention to so form the same as to conceal or camouflage as much as possible from the vision of the average casual observer the overlapping position of the corner piece.

A further object of my invention is to provide a corner piece of the character above mentioned having its vertical edges configured or shaped to taper toward the rear surface thereof whereby to conceal the thickness of the corner piece.

A further object is to provide a corner piece having a rigid base coated with waterproofing and decorative material to which a masonry simulating design is applied, and wherein the opposite longitudinal edges of the corner piece taper toward their rear surface to permit merging of said design with the design on the siding panels overlapped by said corner piece.

A further object is to provide a corner piece adapted to be positioned in overlapping relation to siding panels which is constructed to present

the least possible projection against which objects can strike to injure the same.

Other objects will be apparent from the description and appended claims.

5 In the drawing:

Fig. 1 is a fragmentary perspective view of a side wall of a building illustrating the appearance of my improved corner piece in relation thereto.

10 Fig. 2 is a perspective view of my improved corner piece.

Fig. 3 is an enlarged horizontal sectional view taken on line 3—3 of Fig. 1.

15 Fig. 4 is a fragmentary cross sectional view similar to Fig. 3 and illustrating a modified form of my invention.

Referring to the drawing, which illustrates the preferred embodiment of the invention, the numeral 10 designates a building wall formed from 20 a plurality of panels of siding material. Each of these panels preferably comprises a composition board base 11 having applied to the outer face thereof a coating 12 of asphalt, bituminous, or other waterproofing material which is suitably 25 coated with coloring and surfacing material (not shown) such as brick particles, grit or granules. The face of each panel has a design applied thereto in any suitable manner to provide a plurality of horizontal lines 13 simulating horizontal 30 mortar joints of a different color and appearance than the remainder of the face of the panels, and also vertical panel lines 14 extending between the lines 13 and in staggered relation to simulate vertical mortar joints. It will be understood that 35 the lines 13 and 14 may be of any conventional character, and as here illustrated are depressed at 15 to give the appearance of raked mortar joints. Lines 13 and 14 may have the bituminous material or asphalt 12 exposed for color 40 contrast with the surfacing material, or may be formed by grit or granular material of a color contrasting to that applied to the remainder of the panels which are outlined thereby to outline 45 simulated masonry elements such as the brick faces 16.

My corner piece 17 is formed in the same manner and of the same materials as the wall panels heretofore described, and utilizes the composition board 11 and waterproofing and decorative 50 coating 12 as aforesaid. The opposite longitudinal edges of the corner 17 are tapered at 18. As illustrated in Fig. 3 this taper may be a straight taper extending from the rear edge of the board 11 at an acute angle and merging at 19 with the face of the board 11 on a gradual

curve which tends to eliminate therefrom the appearance of a corner. The weather proof and decorative coating material is extended to cover the tapered edges 18 at 20. A plurality of horizontal mortar simulating lines 21, shown in Fig. 3 as comprising depressions and similar in all respect to the lines 13 and 14 in the siding panels 10, serve to impart to the outer face of the corner unit the appearance of a plurality of masonry units such as brick faces 22.

It will be observed that, by this corner construction, the tapered ends 18 together with the curved corner 19 tend to conceal and camouflage the three dimensional character of the coating at the longitudinal edges of the corner pieces, regardless of the angle from which the same is viewed. In this connection, it will be obvious that when any corner structure is viewed from an angle such as Fig. 2, this overlapping position of the corner piece with respect to the side walls of the building, is not particularly noticeable, even with the present day corner construction utilizing the straight perpendicular edges. However, when the conventional corner piece is viewed at an angle, as in Fig. 1, the thickness of a straight edge corner piece is readily apparent. In the instant construction, the curvature of the outer corner of the corner piece at 19, together with the tapered form thereof, produces a different optical effect than a straight edge panel, as best illustrated in Fig. 1. The offset relation of the corner piece to the side wall is substantially concealed.

Another important advantage of this improved corner is that the mortar joint simulations thereof match better with those of the overlapped siding panel and thereby avoid an objectionable break-joint appearance. Still another advantage of the construction is that it does not provide a projection or shoulder of such character as to be readily damaged if struck a glancing or end blow. There are various other ways by which the same advantages aforesaid can be achieved. Thus a modified form of the longitudinal edge

of a corner piece is illustrated in Fig. 4, wherein said edge is formed on a gradual curve 25 merging with the outer face of the panel 11 and meeting the rear face of the panel 11 in acute angle relation. Some individuals may prefer the curved form as illustrated in Fig. 5 to the straight tapered form illustrated in Fig. 3, but the results in both instances are the same.

I claim:

- 10 1. A building corner piece adapted to overlap end portions of building panels each simulating a plurality of masonry faces mounted on side walls adjacent a building corner, comprising a pair of fixedly angularly disposed narrow elongated rigid panel portions, the outer longitudinal edges of said panel portions being tapered and merging in a gradual curve with the outer faces of said panels, said tapered portions each defining an acute angle with the rear surfaces of said panel portions, and a waterproof and decorative coating covering the outer faces and tapered portions of said panel portions and simulating a plurality of masonry faces and adapted to complement the pattern of masonry faces on said panels.
- 15 2. A building corner piece adapted to overlie end portions of building covering panels on adjacent building walls and each having a plurality of horizontal mortar joint simulations, comprising a vertically elongated rigid member of L-shape in cross section, said member having its opposite longitudinal edges tapered from front to rear to conceal the thickness thereof when in overlying relation to said panels, said member having a plurality of horizontal mortar joint simulations extending thereacross and across said tapered edges to merge with the joint simulations of said panels.
- 20 3. A building corner piece as defined in claim 2, wherein said tapered edges are curved to merge with the respective front faces of said member and to form acute angles with the respective rear faces of said member.

HENRY A. MULDERINK.
